Primary Examiner — Jae Liang*Assistant Examiner* — Tia Ruth-Renee Polidori(74) Attorney, Agent, or Firm — Bochner IP, PLLC;
 Andrew D. Bochner(57) CLAIM

I claim the ornamental design for a cigar glass, as shown and described.

DESCRIPTION

FIG. 1 is a top, front perspective view of a cigar glass; FIG. 2 is a front elevation view thereof; FIG. 3 is a rear elevation view thereof; FIG. 4 is a left-side elevation view thereof; FIG. 5 is a right-side elevation view thereof; FIG. 6 is a top plan view thereof; FIG. 7 is a bottom plan view thereof; and, FIG. 8 is an environmental perspective view of FIG. 1. The dot-dash broken lines define the bounds of the claim and form no part of the claimed design. The dash-dash broken lines depict environment that forms no part of the claimed design.

1 Claim, 4 Drawing Sheets(56)
